Paul Voss, Solingen-Wald, Germany, assignor to Carl
Prinz A. G. für Metallwaren, Solingen-Wald, Germany

Application April 25, 1955, Serial No. 35,669

Term of patent 7 years

(Cl. D22—3)

Fig. 1 is a top edge view of a knife showing my new design;

Fig. 2 is a side elevational view thereof; and

Figs. 3, 4 and 5 are respectively enlarged sectional views thereof taken on lines 3—3, 4—4 and 5—5 of Fig. 2.

The essential features of the design reside in the portions shown in full lines in the drawing.

I claim:

The ornamental design for a knife, substantially as shown and described.
